UNITED STATES PATENT OFFICE.

PHILIP K. YOUNG, OF OMAHA, NEBRASKA.

CLOTHES-REEL.

SPECIFICATION forming part of Letters Patent No. 742,270, dated October 27, 1903.

Application filed May 17, 1901. Serial No. 60,767. (No model.)

To all whom it may concern:

Be it known that I, PHILIP K. YOUNG, residing at Omaha, in the county of Douglas and State of Nebraska, have invented certain useful Improvements in Clothes-Reels; and I do hereby declare that the following is a full, clear, and exact description of the invention, such as will enable others skilled in the art to which it appertains to make and use the same, reference being had to the accompanying drawings, which form a part of this specification.

This invention relates to an improvement in clothes-reels.

15 The object of my invention is to provide an improved clothes-reel so arranged that the clothing may be readily placed upon the reel, which is then raised upward to carry the same a suitable distance above the ground, so that 20 the wind may easily get at the same, as will be more fully described hereinafter.

25 In the accompanying drawings I have shown in Figure 1 a top view, with portions removed, of the clothes-reel embodying my invention. Fig. 2 shows a side elevation with portions removed. Fig. 3 shows a broken detached detail disclosing the arrangement of the rack, while Fig. 4 discloses an enlarged 30 sectional detail of the turn-table as used in my invention.

35 My invention embodies, essentially, an ordinary tube 2, which above is provided with a collar 3, through which projects a pin 4. At a suitable point this tube is slotted, so that a pinion 15 may enter the tube, this pinion being supported by means of a holder 8, which is provided with the projections 13, through which the stub-shaft 14, supporting the pinion 15, passes. This holder 8 is secured by 40 means of suitable bolts or screws 10 and 12. Projecting from the shaft 14 is a crank 16, so that this pinion 15 may be rotated. Depending from the bolt 10 is a pawl 30, engaging the pinion 15, so that this pinion may be held 45 at any suitable position by means of this pawl. Sliding within the tube 2 is a pole 6, this pole being provided with a groove 5, within which groove the end of the pin 4 works to prevent this pole 6 from revolving. Along the lower 50 part of this pole 6 is a rack 7, which rack is engaged by and meshes with the pinion 15, so that this bar 6 may be raised and lowered by

means of the crank-operated pinion 15. Secured to the top of this pole 6 is a plate 18, which plate at a suitable point is provided 55 with an opening, so that the end of a latch 21 may pass through the plate 18. This plate is fixed to the pole 6. Projecting from the plate 18 are the ears a, which support the pin p, and this pin supports the latch 21, this latch 60 being provided with a weight c, so that the latch is normally adapted to work through the plate 18 and engage an opening within the turn-table 23 to lock this turn-table and the plate 18.

65 The turn-table 23 freely revolves upon the plate 18 and is held by means of a pin 25, which passes through the supporting-bars 24 and then enters the pole 6 to properly hold the turn-table 23. This turn-table is provided with a ring 31, as is shown in Fig. 1, so as to hold and receive the upper end of the pole 6. The turn-table 23 is provided with a number of sockets, (marked 1,) which sockets are secured to the turn-table, and these 70 sockets 1 in turn are provided with the supporting-bars 24, which rest upon and revolve upon the upper end of the pole 6. Now normally the turn-table by means of the bars 24 is supported upon the upper end of the 75 pole 6, and the latch 21 is normally in engagement with the turn-table 23, so that the turn-table is locked or removably held. Now in order to permit a free rotation of the turn-table 23 an operating-rope 26, which passes 80 through an eyelet 32, secured to the plate 18, is secured to the weighted end of the latch 21 and drawing down this rope disengages the latch from the turn-table, and a little swinging plate 19, provided with an extending 85 thumb-piece, is then swung below the latching end of the latch 21 to hold the latch out of its seating. In Fig. 3 the plate 19 is shoved below the latch, so that the turn-table 90 may freely revolve. Working within the 95 sockets 1 are a number of rack-bars K, provided with the eyelets a', through which a suitable clothes-line passes. In Fig. 4 I have shown a sectional detail disclosing the rack-bar and a turn-table supporting the same.

100 After the clothes have been secured to the clothes-line, while the pole 6 is in its lowermost position, the pinion 15 is operated to raise the pole a suitable height, so that the clothes

will be held at least a distance of six feet from the ground, so that pedestrians may freely pass under the same. Being at such an elevation, the clothing is engaged by the 5 wind to revolve this reel, so that the washing becomes speedily dried. The pole is held in its uppermost position by locking the pinion.

The parts are all simple in construction and easily operated, and, 10 Having thus described my said invention, what I claim as new, and desire to secure by United States Letters Patent, is—

In a clothes-reel of the character described, the combination with a pipe, of a pole sliding 15 in said pipe, means for raising and lowering said pole, a horizontal plate around the upper

end of said pole, provided with an opening, a turn-table provided with supporting-bars working upon the upper end of said pole and a ring surrounding said pole, and also provided with an opening registering with the opening in said plate, a latch pivoted on said plate and having one end normally extending into said openings, a stop pivoted to said plate so as to swing between the plate and 20 latch, and clothes-supporting means attached to said turn-table. 25

PHILIP K. YOUNG.
